UNITED STATES PATENT OFFICE

2,461,779

ROAD SANDER

Elmer J. Schall, Germania, Pa.

Application April 12, 1948, Serial No. 20,572

3 Claims. (Cl. 291—23)

1

This invention relates to a novel sander adapted to be secured to an automotive vehicle or airplane for blowing sand on the road directly in front of the driving wheels to prevent slippage.

The primary object of this invention is to provide a sander controlled by a switch on the dash of an automotive vehicle associated with a signal on the dash for indicating whether the sander is on or off, and for delivering sifted sand or ashes directly in front of the driving wheels while air-drying the sand or ashes.

Another object of this invention is to provide a sander for delivering air dried sand to the road directly in front of the driving wheels of an automotive vehicle which sander is provided with a motor driven conveyor and a fan for drawing warm air from a by-pass in the air exhaust conduit leading to the muffler.

Yet another object of the invention is to provide a sander having a removable sand reservoir.

These, together with various ancillary objects and features of the invention which will later become apparent as the following description proceeds, are attained by the device, a preferred embodiment of which has been illustrated by way of example only in the accompanying drawings, wherein:

Figure 1 is a side elevational view partly in perspective of the sander attached to an automotive vehicle;

Figure 2 is a bottom plan view of the sander as shown in Figure 1;

Figure 3 is a longitudinal vertical sectional view of the sander housing and associated parts;

Figure 4 is an end elevational view of the sander housing looking to the right on Figure 1;

Figure 5 is a transverse vertical sectional view taken substantially on the plane of section line 5—5 of Figure 3;

Figure 6 is another transverse vertical sectional view taken substantially on the plane of section line 6—6 of Figure 3;

Figure 7 is another transverse vertical sectional view taken substantially on the plane of section line 7—7 of Figure 3;

Figure 8 is a transverse vertical sectional view taken substantially on the plane of the section line 8—8 of Figure 1;

Figure 9 is a longitudinal sectional view through the hose and nozzle attachment taken substantially on the plane of section line 9—9 of Figure 2;

Figure 10 is a transverse vertical sectional view through the fan shaft taken substantially on the plane of section line 10—10 of Figure 3; and

2

Figure 11 is a diagrammatic view of an electrical circuit showing the interconnection between the motor, light, battery, and dash switch.

Specific reference will now be had to the drawings. In the several views, similar reference characters indicate corresponding elements throughout.

Indicated generally at 10 is an automotive vehicle having a chassis 12, wheels 14, a muffler 16, 10 a hot air exhaust conduit 18 communicative with the muffler and a dash (not shown).

Removably secured to the chassis 12, in a manner to be later described, is a sander housing 20 which consists of a forward portion 22, which is 15 preferably a hollow cylinder, a rear portion 24, which is also preferably a hollow but somewhat enlarged cylinder, and a longitudinal tubular portion 26. The forward portion 22 and the bottom portion 26 are separated from the back portion 24 by means of a transverse plate 28, a longitudinal plate 30 welded at right angles to the plate 28, and another transverse plate 32 welded at right angles to the end of the plate 30. A closure plate 34 is provided at rear end of the housing 20 which is spaced from the plate 32 forming therebetween a rear cylindrical portion 36. The forward portion 22 is separated from the bottom tubular portion 26 by means of a longitudinal arcuate plate 38 which is provided with a longitudinal slot 40.

Slidably and removably positioned in the forward portion 22 is a substantially cylindrical sand reservoir 42 whose diameter is somewhat less than that of the portion 22, which reservoir carries a 35 substantially C-shaped handle 44 at its forward end and a longitudinal slot 46 in the side wall thereof. When the slots 40 and 46 are manually aligned, sand S will flow by gravity from the reservoir to the tubular portion 26 therebelow.

Secured to the forward end of the tubular portion 26 and to the bottom of the plate 28 is a pair of bearings 48 and 50 respectively. Rotatably journalled through the tubular portion 26 and 45 through the bearings is a spiral conveyor 52 whose shaft 54 extends longitudinally through the bottom of the rear portion 24, the rear end of which shaft is rotatably journalled to the plate 32 as at 54. Intermediate the plates 28 and 32, the conveyor shaft 54 carries a sheave 56.

Resiliently mounted to the inner walls at the top of the housing 20 in the rear portion 24 by means of appropriate bolts 58 carrying springs 60 is a motor 62 having a drive shaft 64 to the end 55 of which is secured a sheave 66. Also secured

to the drive shaft between the sheave 66 and the motor is a smaller sheave 68.

Longitudinally and rotatably disposed substantially through the center of the rear portion 24 is a fan shaft 70 which extends through an aperture in the plate 32 and is journaled at its forward end to the closure plate 34 as at 72. The rear end of the fan shaft is journaled in a collar 74 which is pivotally secured to the plate 28 by means of a screw 76. The fan shaft carries a sheave 78. An endless web 80 is entrained over the sheaves 66 and 78.

Resiliently mounted to the inner walls of the housing 20 within the rear portion 28 by means of appropriate hooks 82 and springs 84 are a pair of shafts 86 and 88. The shaft 86 carries a larger sheave 90 and a smaller sheave 92 while the shaft 88 carries a larger sheave 94 and a smaller sheave 96. Entrained over the sheaves 68 and 94 is an endless web 98, while another web 100 is entrained over the sheaves 90 and 96. Entrained over the sheaves 92 and 56 is another web 102. A fan 104 is secured to the fan shaft 70 within the rear portion 36. Thus it will be seen that the motor drivingly engages the fan and the spiral conveyor.

The housing 20 is further provided with an aperture 106 adjacent the sand reservoir which is communicative with a flexible conduit 108 which is connected to a heating chamber 110 which in turn is clamped around the air exhaust conduit 18 normally communicative with the muffler 16. When the fan is turning, warm air is drawn from an aperture 111 in the chamber 110 through the conduit 108 and thence through the sand in the reservoir.

Communicative with the upper portion of the rear portion 36 is an air-inlet conduit 113 threaded at its free end to receive an internally threaded screened cap 112. Communicative with the lower portion of the rear portion 36 of the housing is a sand outlet conduit 114 in which is secured a Y-shaped couple 116 which is communicative with a pair of sand delivery conduits 118 and 120 which carry at their free ends a pair of downwardly and rearwardly inclined nozzles 122 and 124. The nozzles are provided with an upstanding apertured lug 126 which receives an appropriate bolt or screw and nut 128 for securing said lug to a bracket 130 removably secured to the chassis adjacent and in front of the driving wheels 14.

As shown more particularly in Figure 4 a pair of clamps 132 and 134 around the forward portion and rear portion of the sander housing 20 are provided for removably securing the housing to the chassis 12. The clamps are arcuate collar clamps fixedly secured by means of a bolt or screw at one end to the chassis as at 136 and removably secured to the chassis at the other end by means of a hinge 138 having a longitudinal slot therein (not shown) through which extends a threaded finger 140 which in turn extends through an angulated lip 142 integral with the end of the arcuate clamp. The finger 140 re-

ceives a wing clamp 144. The sand reservoir 42 is additionally secured in the housing forward portion 22 by means of a conventional friction catch 146.

As shown in Figure 11, the battery B normally provided in the vehicle 10 is operatively connected to a switch SW which is preferably provided on the dash (not shown). The switch is operatively connected to a light L on the dash and the motor 62.

In view of the foregoing description taken in conjunction with the accompanying drawings it is believed that a clear understanding of the device will be quite apparent to those skilled in this art. A more detailed description is accordingly deemed unnecessary.

It is to be understood, however, that even though there is herein shown and described a preferred embodiment of the invention the same is susceptible to certain changes fully comprehended by the spirit of the invention as herein described and the scope of the appended claims.

Having described the invention, what is claimed as new is:

25. 1. In a motor vehicle having a chassis, rear wheels, and an air exhaust conduit; a sander comprising an elongated housing secured to said chassis having an upper compartment, a rear compartment and a lower compartment, said lower compartment having an upper wall including an elongated opening, a sand reservoir slidably and rotatably positioned in said upper compartment, said reservoir including a wall having an opening registrable with said first-mentioned opening, a screw conveyor rotatably journaled in said lower compartment, means in said rear compartment for driving said conveyor, nozzles secured to the chassis in front of the rear wheels, sand delivering conduits interconnecting said nozzles with the rear of said lower compartment, and means for drawing warm air through said upper and lower compartments.

2. The combination of claim 1 wherein said first-mentioned means includes a motor resiliently mounted in said rear compartment.

3. The combination of claim 2 wherein said last-mentioned means includes a jacket about said exhaust conduit having an air-inlet port therein, an air inlet conduit interconnecting said jacket and said upper compartment, a fan mounted in said rear compartment and drivingly connected to said motor, and a restricted air inlet in the rear compartment adjacent said fan.

ELMER J. SCHALL.
